UNITED STATES PATENT OFFICE.

JOHN A. JUTEN, OF GILBERT, MINNESOTA.

COLLAPSIBLE COT

1,276,539.

Specification of Letters Patent. Patented Aug. 20, 1918.

Application filed August 13, 1917. Serial No. 185,933.

To all whom it may concern:

Be it known that I, JOHN A. JUTEN, a citizen of the United States, residing at Gilbert, in the county of St. Louis and State of Minnesota, have invented certain new and useful Improvements in Collapsible Cots; and I do hereby declare the following to be a full, clear, and exact description of the invention, such as will enable others skilled in the art to which it appertains to make and use the same.

This invention relates to new and useful improvements in collapsible cots, and has for its primary object to produce a cot of this character which is of comparatively cheap and inexpensive construction, durable and substantial in design, and which can be quickly and readily collapsed into a compact bundle so as to occupy a minimum amount of space.

A further object of the invention is to provide means for locking the cot in extended or set up position.

A still further object of the invention is to construct the cross legs of the cot of detachable sections so that when the cot is collapsed, the sections can be disconnected in order to enable the cot to be arranged in a more compact and smaller bundle.

With these and other objects in view as will appear as the description proceeds, the invention comprises the various novel features of construction, combination and arrangement of parts as will be more fully described hereinafter and set forth with particularity in the appended claims.

Referring to the drawings,

Figure 1 represents a side elevation of my improved construction of collapsible cot.

Fig. 2 represents an end view of the cot.

Fig. 3 represents a side elevation of the cot collapsed, with the lower sections of the cross legs removed, and

Fig. 4 represents a side elevation of one of the lower cross leg sections.

Similar characters of reference are used to denote corresponding parts throughout the accompanying drawings and the following description.

Referring more particularly to the drawings, the reference numeral 1 indicates a pair of parallel side members and the numeral 2 indicates a pivotal member coextensive in length with the side members and arranged in a plane below and intermediate the side members. The side members are connected

through the medium of a canvas or other fabric top 3.

Each of the parallel side members is constructed of telescopically mounted pipe sections 4, 5 and 6. The pivotal member likewise is constructed of a plurality of pipe sections 7, 8 and 9. The side members 1 and the pivotal member 2 have their opposite ends and their intermediate portions supported through the medium of pairs of cross legs 10.

The legs of each pair of cross legs each consist of an upper section 11 and a lower section 12, the upper end of the lower section being threaded into the lower end of the upper section for detachable connection therewith. The lower end of each of the upper sections 11 is provided with a bearing 13 for the reception of the pivotal member 2, while the upper end of each upper member is provided with a bearing 14 for the reception of the respective side members.

When the cot has been arranged in set up position, I employ a pair of hooks 15 in connection with each pair of cross legs to rigidly maintain the same in set up position. The upper ends of these hooks 15 are pivotally connected to the upper leg sections 11, as indicated by the numeral 16, while the lower hook ends are adapted to engage eyes 17 carried by the lower leg sections 12.

In order to maintain the cot in extended position against casual telescoping, I provide spring catches 18 for each of the pipe sections 8 and 9, these spring catches consisting of a leaf spring rigidly secured at one end to each of the respective sections 8 and 9, while the opposite end is provided with a lug adapted to engage a corresponding aperture in each of the respective pipe sections 7 and 8 when the sections have been extended. While I have shown one form of spring catch for holding and maintaining the pipe sections in extended position, I of course desire it to be understood that any other form of spring catch means may be used within the scope of the claims.

I claim:

1. A collapsible cot comprising a pair of parallel telescopic side members, a fabric top connecting said side members, a pivotal telescopic member arranged in a plane below said side members, pairs of cross legs pivotally mounted on the opposite ends and the intermediate portion of said pivotal member, the upper ends of said cross legs supporting

the opposite ends and the intermediate portions of said side members, and means for locking the telescopic pivotal member in extended position.

- 5 2. A collapsible cot comprising a pair of parallel telescopic side members, a fabric top connecting said side members, a telescopic pivotal member coextensive in length with and disposed in a plane below said side members, pairs of cross legs pivotally mounted on the opposite ends and the intermediate portion of said pivotal member, the upper ends of said cross legs supporting the

opposite ends and the intermediate portions of said side members, each of said cross legs 15 consisting of detachable connected sections, and means for locking each pair of cross legs in set up position with respect to each other.

In testimony whereof I have signed my name to this specification in the presence of 20 two subscribing witnesses.

JOHN A. JUTEN.

Witnesses:

P. R. COSGROVE,
JOHN PAEKI.
